WATERPROOF WRAP-AROUND SHOE COVERING

Benton F. Thompson, Naugatuck, Conn.

Application November 15, 1946, Serial No. 710,122

8 Claims. (Cl. 36—7.2)

1

This invention relates to footwear, and more particularly to a water-repellant foot or shoe covering adapted to be wrapped around and fastened to a woman's foot and ankle.

One object of the present invention is to provide a "wrap-around" shoe covering of the above nature which will cover the shoe in inclement weather where the protection is most needed.

A further object is to provide a shoe covering of the above nature which will be light in weight and compact so as to permit it to be folded when not in use into a small space and stored in a waterproof envelope which may be carried in the purse or pocket.

A further object is to provide a simple waterproof covering of the above nature which may be adjusted to and wrapped tightly around any size shoe or foot.

A further object is to provide a wrap-around foot covering of the above nature which will be practical to use on a wide variety of sizes and lasts of shoes, including the "platform" or "wedgie" types, and which on account of its adjustability and soft draping qualities will be "molded" to fit the foot so as not to interfere with the bow or buckle worn on the shoe.

A further object is to provide a shoe or foot covering of the above nature which will be simple in construction, inexpensive to manufacture, easy to install and manipulate, ornamental in appearance, and very efficient and durable in use.

With these and other objects in view, there has been illustrated on the accompanying drawing one form in which the invention may conveniently be embodied in practice.

In the drawing,

Fig. 1 represents a perspective view of the improved "wrap-around" shoe covering as it appears when worn upon a woman's shoe and foot.

Fig. 2 is a perspective view of the same, as it appears when the attaching straps have been unbuckled, and one side flap of the covering swung downwardly preparatory to removing it from the foot and shoe.

Fig. 3 is a bottom plan view of the blank from which the "wrap-around" shoe covering may be formed by folding and stitching.

Fig. 4 is a transverse sectional view of the same, taken through the center of the sole along the line 4—4 of Fig. 3, looking in the direction of the arrows.

Referring now to the drawings in which like reference numerals denote corresponding parts throughout the several views, the numeral 10 indicates a four-sided blank having a pair of rounded central tabs 11, 12 at the forward portion thereof. The tabs 11, 12 are adapted to be stitched together by a line of stitching 13, as clearly shown in Figs. 1 and 2 of the drawing.

The blank is also provided with a pair of side

2

cover flaps 14, 15 of identical shape, having a pair of notches 16, 17 adjoining the outer ends of the curved tabs 11, 12, respectively for facilitating the binding of the transverse forward edges of the cover flaps 14, 15 in a sewing machine.

Between the two forward tabs 11, 12, the blank 10 is cut to provide a substantially triangular tab 18, which is adapted to be bent upwardly and rearwardly so as to overlie the sole portion of the shoe covering when worn on the shoe. The tab 18 is then preferably stitched to the blank 10.

In order to permit the stitching of the rear of the cover flaps 14, 15 together under the instep and in front of the heel H of the shoe S (see Figs. 1 and 2), provision is made of a pair of V-notches 19, 20, as clearly shown in Fig. 3 of the drawing.

The notches 19, 20 permit the rear of the shoe covering to be suitably molded to the shape of the shoe.

Located between the V-notches 19, 20 is a central rear tab 21 underneath the instep arch of the shoe, and conforming to the curvature thereof.

Provision is also made of a sole tread 22, substantially oval-shaped, as clearly shown in Fig. 3, which tread 22 is secured to the underside of the blank 10 by means of a layer of self-curing cement 23, or by stitching, or both. It may also be attached by vulcanization.

The outer sides of the cover flaps 14, 15 are provided with angular end sections 24, 25, having a pair of obtuse corners 26, 27 at the forward portions thereof—said obtuse corners being adapted to be folded under the instep arch of the shoe S.

Provision is also made of a pair of rear acute angle corners 28, 29, which are adapted to be folded over the instep and the ankle A of the shoe above the heel H.

In order to secure the cover flaps 14, 15 together, provision is made of a pair of snap fastener posts 30, 31 located at the corners 26, 29.

The post 31 is adapted to be secured by means of a longitudinal flexible elastic strap 32 to the corner 28. Provision is also made of a transverse elastic strap 33 stitched to the corner 27. The straps 32, 33 have adjustable buckles 34, 35, respectively, which are provided with snap fasteners 36, 37, respectively.

Operation

In operation, the blank 10 will have its toe tabs 11, 12 stitched together to form a cradle for the toe of the shoe S, as shown in Figs. 1 and 2. The side flaps 14, 15 will then be folded over the shoe as illustrated in Fig. 2, and the snap fastener buckles 34, 35 connected to the snap fastener posts 30, 31.

It will be understood that the strap 32 will be located around the rear of the ankle A of the

foot, while the strap 33 will be located underneath the instep part of the shoe S.

It will also be clear that the adjustable buckles 34, 35 may be moved along the straps 32, 33 to any desired positions according to the size and shape of the foot and shoe, and may thereafter be attached or detached without further adjustments being required.

The shoe covering blank 10 may be constructed from any desired water-repellant or waterproof sheet material such as rubber, fabric, plastic, or film, and may be of any desired color, and transparent or otherwise.

It will be understood that the shoe covering may also consist of a one- or two-piece upper depending upon solid or multi-color combinations employed.

It will be understood that instead of stitching the tabs to the flaps as herein illustrated, these parts may be connected to the blank by cement or fastener elements, within the spirit and scope of this invention.

It will also be understood that instead of employing snap fasteners for connecting the straps to the cover flaps, hooks may also be used within the purview of this invention. Moreover, the straps may be made of fabric or plastic and may be elastic or not, within the scope of the present invention.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short the invention includes all the modifications and embodiments coming within the scope of the following claims.

Having thus fully described the invention, what is claimed as new, and for which it is desired to secure Letters Patent, is:

1. In a foot or shoe covering, a flexible sheet

of material having a central tread secured to the bottom of said sheet, a pair of forward curved tabs secured together to form a cradle for the toe of the shoe or foot, a flexible elastic transverse strap connected to one side of the sheet for passing under the instep arch and detachably connected to the other side of said sheet, and a second flexible strap connected to the other side of said sheet for passing around the rear of the ankle being detachably secured to the first mentioned side of said sheet.

2. The invention defined in claim 1, in which said straps are secured to the sides of said sheet by means of snap fasteners.

3. The invention defined in claim 1, in which the inner sections of said tabs are provided with curved sections which are stitched together to form said cradle.

4. The invention defined in claim 1, in which 20 a pair of curved forward central tabs are provided to form the cradle thereof, and notches are provided at the outer portions of said tabs to permit the binding of the raw edges of the forward portions of the sides of said sheet.

5. The invention defined in claim 1, in which 25 said sheet is provided with a rear central tab underlying the instep arch of the shoe.

6. The invention defined in claim 1, in which 30 said straps are provided with adjustable buckles for connection with fastener members on the edges of said sheet.

7. The invention defined in claim 1, in which 35 adjustable snap fastener buckles are provided on said straps for cooperation with snap fastener studs secured to the outer portions of said side sheets.

8. The invention defined in claim 1, in which 40 a pair of curved tabs are provided at the forward inner portions of said sheet, said tabs enclosing a triangular tab which is adapted to be bent over the top of said sheet above said tread.

BENTON F. THOMPSON.
